TOY LOCOMOTIVE

Robert Silverstein, Los Angeles, and Robert J. Mortonson,
Alhambra, Calif., assignors to Eldon Manufacturing
Co., Los Angeles, Calif., a corporation of California

Application February 7, 1957, Serial No. 44,789

Term of patent 14 years

(Cl. D34—15)

FIG. 1.

FIG. 2.

FIG. 3.

FIG. 4.

FIG. 5.

Figure 1 is a top plan view of a toy locomotive, showing my new design;

Figure 2 is a side elevational view, the opposite side having substantially the same appearance;

Figure 3 is a bottom plan view;

Figure 4 is a rear elevational view; and

Figure 5 is a front elevation view thereof.

We claim:

The ornamental design for a toy locomotive, as shown and described.
